FOLDABLE METAL FURNITURE

Udo K. Johannsen, Cortland, N. Y.

Application December 17, 1937, Serial No. 180,418

5 Claims. (Cl. 155—55)

This invention relates to certain novel structural improvements directed to a folding metal chair or the like portable folding furniture of which the leg understructure and the back are adapted to collapse upon each other when not extended for use. Chairs of the kind herein devised are more particularly intended for service in households, also in schools, hotels, theaters or the like auditoriums. In collapsed condition, my folded chairs may be compactly stacked for storage on trucks.

The present folding chair or the like device essentially comprises a seat and a back member that may be folded in superimposed relation, and further provides for a relatively yielding seat understructure or U-shaped base frame preferably formed from metal tubing or the equivalent thereof in modernistic fashion to include a pair of yoke interconnected floor contacting foot components and mated upstanding leg components, of which latter the free terminals are respectively equipped with knee joints. Such knuckle joints may be operatively spanned by a U-shaped frame having an upholstered back. If desired, the rear edge of my seat panel may be provided with a hinge pintle so as to tilt rearwardly toward said back in theater seat fashion.

The object of my improvements is to provide for a low cost, sturdy and comfortable foldable metal chair structure of the character indicated that possesses the minimum of articulated fulcrum points and one that when folded, can be compactly stacked for storage.

Embodied herein are also other structural features designed to facilitate the end in view and all of which will presently be pointed out in detail. Reference is had to the accompanying two sheets of drawings that are illustrative of preferred embodiments and in which:

Fig. 1 represents a perspective view of my erected chair with its seat panel lowered into operative position, while Fig. 2 is a similar view showing the seat panel raised rearwardly toward its back panel.

Figs. 3 and 4 respectively show an elevational front and a side view of the Fig. 2 disclosure.

Fig. 5 details in enlarged scale, a pintle portion for mounting my raisable seat panel as taken along line 5—5 of Fig. 1.

Figs. 6 and 7 respectively show a front and a side view of my stackable chair in its folded position.

Figs. 8 and 9 respectively detail a knuckle joint as herein used in its unfolded chair position,

while Figs. 10 and 11 correspondingly show the same joint in folded chair position.

Fig. 12 fragmentally presents a modified back frame structure.

Referring more specifically to the drawings, 10 collectively represents a yieldable U-shaped base frame preferably but not necessarily formed from high carbon tubular steel to impart a limited amount of resiliency to my seat when loaded in use. Said understructure may comprise a pair 10 of spacedly aligned floor contacting rail components 11 and 12 that may be slightly inclined in a common plane and of which corresponding ends may be integrally interconnected by the yoke-like cross-member 13. The respective opposite 15 ends of the rail components 11 and 12 are sharply upturned to erect thereon mated leg components 14 and 15 of which the free terminal regions may be laterally inset as at 14A and 15A relative to the width spacing given to the floor 20 contacting rails. The upper ends of said legs respectively carry a kneelike knuckle joint such as 16 and 17.

The complementary back section or frame 18 of my foldable chair may be given a similar but 25 reversed U-shape to comprise a pair of seat carrying rails 19 and 20 that in unfolded position lie in substantial parallelism over the foot rail components 11 and 12. The free terminals of such seat rails respectively cooperate with the 30 joints 16 and 17. The rear end of said seat rails are sharply bent to comprise the back uprights 21 and 22 of which the yoke region may in turn be cross-connected by an integral tie piece 23 as in Fig. 1, or by the upholstered back panel 24 35 itself in the Fig. 12 manner. In the latter disclosure, a non-continuous flexible back frame made from duplex strap irons or laterally yieldable strip stock 25 is resorted to in lieu of an integral tubular structure. In either case, the 40 back panel may be fixedly held in place by any suitable means, preferably by the screws 26.

The upholstered seat panel 28 may be fixedly or tiltably applied across the base rails 19 and 20, it being preferred to provide for an apertured 45 seat bracket 29 with a pintle 30 entered therethrough and having pintle ends that are received within tubular seat rails as in Fig. 5. Such disposition permits the seat panel to be raised from its operative Fig. 1 position into that 50 shown in Fig. 2, which initial tilting also facilitates the folding of my base and back frames.

The back frame may be bodily swung about its knee joints 16 and 17 through the dotted shift position of Fig. 4 so that the folded frame 55

may ultimately assume the nested V-like relationship represented in Figs. 6 and 7. After being thus folded and shifted through more than 180°, a plurality of these chair frames may be compactly stacked as indicated by dotted outline in Fig. 7 and stored away in a suitable rack or the like carrier having rollers thereunder. In the last named figure, the seat panel 28 when tilted, is made to lie above the plane of the base rail components 11 and 12 while the back panel 24 lies therebeneath.

The special disposition given to my stop knuckle joint is conducive to a close stacking in the manner herein contemplated. To this end, the knuckle pivot 31 is kept well forward of the leg axis by the distance designated J in Figs. 9 and 11 so as to exceed the diametral size of the tubular leg 15. Each such knee joint when embodied as a forging, preferably comprises abutting complementary fittings 32 and 33 of which the flattened leaf extensions are respectively provided with an enlarged, medial stop lug such as 34 or 35 that integrally terminate in pluglike shanks 36 and 37. One such shank is adapted to be snugly entered into a tubular seat rail 19 or 20 and to be riveted, spot welded or otherwise secured therein, in which instance, the corresponding shank is kept aligned with respect to its leaflike extension. In the mated joint fitting, its leaf extension is axially shifted in right-angled relation to the shank thereof and which latter component may be similarly received within the free end of an erected tubular leg such as 14 or 15.

When my chair is set up for use, the stop lug 34 rests upon the angular lug 35 but when the back frame is fully collapsed, a seat rail 20 will closely lie alongside its adjacent leg 15 as in Figs. 7 and 11 and thereby allow the seat rails 19 and 20 together with the back uprights 21 and 22, to unobstructedly pass between the leg components 14 and 15 into their respective folded positions.

In the present disclosure, the seat panel 28 is preferably made wider than the lateral spacing between its supporting rails 19 and 20 so as to overlap the same. The forward swinging seat edge may also be given a curved lip formation as at 28A to conceal the knuckle joints 16 and 17 therebeneath when the chair is fully unfolded as in Fig. 1. The purpose of the leg offsets 14A and 15A is to provide for any needed augmented lateral spacing between the base rail components 11 and 12 with respect to the seat rails 19 and 20. In order to further stabilize such chair structure and improve its appearance, it is preferred to keep the length of the back tie piece 23 somewhat shorter than the pitch spacing allowed between the knee joints 16 and 17. It will be observed that notwithstanding the use of such relatively wide seat and back panels, the arrangement of my bent tubing is such as to allow the seat to unobstructedly enter between the laterally spaced leg components 14 and 15 for snug collapse.

By suitably increasing the pintle projection J of Fig. 11, a wide seat panel that is devoid of any pintle such as 30, may likewise be collapsed in interposed relation between the carrying rails 19 and 20 and the mated base legs 14 and 15, in which event the latter need not be offset as at 14A and 15A.

As a further refinement, one or both of my stop knuckle joints may be equipped with retaining means to allow the erected chair to be bodily lifted and carried about without tendency to collapse, when gripping the back panel. Such

latching device is shown as incorporated in the stop lug 34 by the use of a spring actuated ball 38 that may be projectingly inset into a drilled hole 39, the hole mouth being slightly crimped inwardly and the ball retained against spring tension at 40 in nib fashion or the like means. Cooperating with such latchable ball is a socket 41 sunk into a mated joint leaf 33 and adapted to releasably receive said ball as in Fig. 9 when the chair is erected. By stepping on the base 10 cross member 13 and deliberately tilting the back frame forwardly, said latch may readily be disengaged for chair collapsing purposes.

When the seat panel is equipped with pintles such as 30 and a plurality of such chairs are linked together and set up in closely spaced rows as in an auditorium, the individual lifting of such seat allows the occupant to rise and step within the base confines so that other patrons may conveniently pass onward between such seat rows. Owing to the inbuilt resiliency provided in my jointed frame structure, the occupant may without fatigue remain comfortably seated for a protracted period. The described knee joints are not only sturdy but when in operative position, serve to transmit a limited amount of base yield to the back panel in a manner substantially identical with that afforded by a conventional unjointed framework of the modernistic tubular type. The present improvements are primarily directed to means for compactly storing away chairs of such conventional type when not in use.

It is believed the foregoing rather explicit disclosure makes apparent to those skilled in this art, the advantages afforded by my simple and low cost folding chair, it being understood that certain changes in the illustrative embodiments thereof may be resorted to in attaining a like result, all without departing from the spirit and scope of my invention heretofore described and more particularly defined in the appended claims.

I claim:

1. Stackable folding furniture comprising a unitary yoke shaped base frame of laterally yieldable metal stock including a pair of fixedly spaced floor contacting base rail components lying in substantial parallelism whose corresponding ends are in unfolded position upturned into mated leg components, complementary knuckle joints respectively applied to each free terminal region of such leg components and which joints have their respective knuckle pivots located forwardly of the leg perimeter next adjacent thereto, a unitary back frame comprising a pair of seat carrying rail components upon which are erected interconnected upright components that are laterally spaced to a lesser distance than the aforesaid base rail components and having corresponding ends of the respective seat carrying rails operatively attached to a different knuckle joint, a seat panel carried between such seat rails, and a back panel mounted upon the upright components of the back frame, the latter frame being swingable about said pivots and serving to unobstructedly collapse the back panel into compact aligned relationship with respect to the base rails.

2. A folding chair comprising a unitary tubular base frame including a pair of fixedly spaced floor contacting base rail components lying in a common plane and having in unfolded position corresponding ends thereof upturned into mated leg components, complementary knuckle joints respectively applied to each free terminal region

of such leg components and having their knuckle pivots located in an axially offset relation to the leg perimeter next adjacent thereto, a unitary back frame comprising a pair of seat carrying rail components upon which are erected interconnected upright components that are laterally spaced to a lesser distance than the aforesaid base rail components and have corresponding ends of the respective seat carrying rails operatively attached to a different knuckle joint, a seat panel mounted across the seat rails, and a back panel fixedly mounted upon the upright components of the back frame, the latter frame being unobstructedly swingable about said pivots to fold said back panel between the base rails into substantial coincidence with the plane thereof.

3. A folding chair comprising a unitary tubular base frame including a pair of laterally spaced floor contacting base rail components lying in substantial parallelism whose corresponding ends are in unfolded position upturned into mated leg components having inturned terminals that are laterally spaced to a lesser distance than the aforesaid base rails, complementary knuckle joints respectively applied to each free terminal region of such leg components and having their knuckle pivots located forwardly of the leg perimeter next adjacent thereto, a unitary back frame comprising a pair of seat carrying rail components upon which at corresponding ends thereof are erected interconnected upright components and having the other rail ends operatively attached to a different knuckle joint, and a panel tiltably mounted across the seat rails and which seat panel has a width greater than the aforesaid inturned leg terminals but less than the base spacing of the respective leg components, said back frame being unobstructedly swingable about said pivots and serving to enter the seat panel between said legs when the back frame is swung into folded position.

4. A folding chair comprising a unitary tubular base frame including a pair of fixedly spaced

floor rail components lying in a common plane whose corresponding rail ends are in unfolded position upturned into mated leg components, complementary knuckle joints respectively applied to each free terminal region of such leg components and which joints have their knuckle pivots located in an axially offset relation to the leg perimeter next adjacent thereto, a unitary back frame comprising a pair of seat carrying rail components upon which at corresponding ends there are erected interconnected upright components and having the other rail ends operatively attached to a different knuckle joint, a back panel fixedly mounted upon said upright components, and a seat panel tiltably mounted across the seat rails and the width of which panel is smaller than the lateral spacing given to the floor contacting rail components of the base frame and enterable between the chair legs, said seat panel in folded chair position being disposed to one side of the aforesaid plane and the back panel being oppositely disposed relative thereto.

5. A folding chair comprising a unitary base frame including a pair of fixedly spaced floor contacting rail components whose corresponding ends in unfolded position, are upturned into mated leg components, a knuckle joint including complementary fittings for each free terminal region of the respective leg components and which joints have their knuckle pivots located in an axially offset relation to the leg perimeter next adjacent thereto, a unitary back frame including a seat panel and a back panel and which frame is operatively attached to both of the knuckle joints, and latchable retaining means disposed between the complementary fittings of one such knuckle joint, said back frame upon release of the retaining means being unobstructedly foldable about said pivots with respect to the base frame for stacking purposes.

UDO K. JOHANNSEN.
